UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS, A CORPORATION OF ILLINOIS.

COIN-DELIVERY MACHINE.

1,099,688.

Specification of Letters Patent. Patented June 9, 1914.

Application filed February 8, 1913. Serial No. 747,120.

To all whom it may concern:

Be it known that I, EDWARD J. BRANDT, a citizen of the United States, residing at Watertown, in the county of Jefferson and 5 State of Wisconsin, have invented certain new and useful Improvements in Coin-Delivery Machines, of which the following is a specification, reference being had therein to the accompanying drawing.

10 This invention relates to an improvement in coin delivery machines of the type known as "Brandt automatic cashier," and the present invention relates more particularly to the type of machine shown and described 15 in my application filed June 10, 1912, Serial No. 702861.

In the particular embodiment of machine illustrated in the application above referred to, there is shown a machine employing a 20 series of coin pushers which are actuated by mechanism including a series of bell crank levers, which levers are actuated singly and associated by a series of keys, which keys are provided with portions 25 adapted to directly engage the arms of the bell crank levers to effect the shifting thereof. In this construction, owing to the fact that it is necessary to employ a series of keys and to the fact that most of such keys are 30 adapted to effect the actuation of more than one of the bell crank levers, the arms of said levers are engaged at varying distances from the pivots thereof by the parts which are moved into engagement therewith when the 35 keys are manipulated, so that it will be found that considerable more power is required to operate some of the keys than to operate other of the keys.

The primary object of the present invention 40 is the provision of a machine of this character in which this objection will not be present in that the pressure required to operate the various keys will be, to a substantial extent, equalized.

45 Other objects of the invention will be apparent from the detailed description herein-after when read in connection with the accompanying drawings forming a part hereof, wherein a convenient embodiment of 50 the invention is illustrated and wherein like characters of references refer to similar parts in the several views.

In the drawings: Figure 1 designates a

vertical section of the improved machine, portions of which have, for the sake of clearness, been omitted. Fig. 2 is a rear elevation of the machine showing the rear wall of the casing removed, parts being broken away and parts shown in section. Fig. 3 is a horizontal section on line 3—3 of Fig. 1. 60 Fig. 4 is a detail view of one of the keys, and Fig. 5 is a detail view of one of the rockers which are utilized to effect the shifting of the bell crank levers.

Referring now more particularly to the 65 drawings, the machine embodies a casing, which is adapted to inclose the various parts of the mechanism, and which may be of any preferred design and construction.

In the present machine a group of vertically reciprocative edge-wise plates 11, such as are usual in "Brandt automatic cashiers" are employed, and as in the construction shown in my application, above identified, each plate is provided with a spring controlled shank 11' which is guided in plates 12 and 13, which are secured within the casing and each of which is connected at its upper end to a suitable push button 14. Each plate 11 and the push button 14 associated therewith, constitutes what is termed a "key" of the machine. As is usual in "Brandt automatic cashiers," the plate portion 11 of each key is provided with a foot or with a plurality of feet 11'', the number 75 of said feet depending upon the number of coin pushers which are adapted to be actuated by the particular key.

In the present machine, as in the machine disclosed in my application herein referred to, a series of edge-wise disposed angle plates are employed, such plates constituting bell crank levers, all of which are conveniently fulcrumed on a rod 16 which is secured in any suitable manner in the frame 90 or casing of the machine and extends transversely thereof. The rear arms of the bell crank levers 15 are adapted to extend horizontally and to underlie the plate portions 11 of the various keys and said arms are 100 also positioned to work in slots formed in plates 35 and 36 which are secured in the casing, this construction serving to properly guide the bell crank levers in their movements. A spiral spring 17 connects the rear 105 arm of each bell crank lever 15 with any

suitable fixed part of the machine and serves to normally hold said lever in its proper position.

Pivots connected at their upper ends to a rod 20 or other suitable support which is mounted in the upper portion of the casing are a plurality of pendant swing hangers 21, there being as many of such hangers provided as there are bell crank levers 15 in the machine. Each hanger is straddled by the forked end of a coin pusher 22, which is pivoted to the hanger adjacent the lower end thereof, the rear end of which coin pusher is connected by a suitable spiral spring to the widened lower end of the hanger 21 to which said pusher is pivoted.

The lower widened end of each hanger 21 is provided with an anti-friction roller 28 which opposes the forward arm of one of the levers 15 which arm is confined between the hanger and a guard 29 parallel thereto, said guard being fast on a spacing rivet 30 and the guard also serving with the hanger as a support for the anti-friction roller 28. From this construction, it will be readily understood that each of the coin pusher hangers is swung forward whenever the lever 15, associated therewith, is rocked from its normal position, and that such hanger is restored to its normal position whenever the spring 17 serves to restore the lever 15, which has been rocked, to its normal position.

The actuation of the coin pusher hangers 21 serves to eject the proper coins from the compartments of a coin tray 31 into a chute 11. The construction of these parts is similar to that disclosed in my application Serial No. 702,861, above referred to, and I have, therefore, deemed it unnecessary to herein fully illustrate and describe in detail, the structure of such parts.

In the structure illustrated in my application, No. 702,861, herein referred to, the bell crank levers are rocked by direct contact of the plates 11 of the keys with the rear arms thereof. By reason of the position which some of these plates must necessarily occupy, on account of the number and character of the keys employed, it will be observed that when some of the keys are depressed, the plates 11 thereof will contact with the bell cranks 15 adjacent the pivots thereof, while in other cases, the contact will be made at some distance from the bell crank pivots, so that considerable more power will be required to operate some of the keys than others. In the present embodiment of the invention, the plates 11 of the keys do not contact directly with the arms of the bell crank levers themselves, but are arranged to contact with intermediate members, one of which is provided for each bell crank lever, which intermediate members are fashioned to engage the arms of the bell crank levers at certain definite fixed points whenever

they are actuated by the depression of the keys, so that regardless of the point at which the key may engage the intermediate member, the engagement of said intermediate member with its bell crank lever will always be at the same point and the pressure which is required to operate the various keys will, therefore, be to a great extent equalized.

In the particular embodiment of the invention illustrated in the present application, the intermediate members used for this purpose to form the operative connections between the keys and the bell crank levers 15 consist of rockers 50, one of which is positioned alongside of the rear arm of each bell crank lever 15, said rockers conveniently comprising bars having crank ends which are journaled in any suitable manner in the frame or casing of the machine, such cranked ends, in the particular embodiment illustrated, being shown as pivotally mounted in the plates 35 and 36. Projecting laterally from each of the rockers 50 is a projection 51 which is adapted to overlie the upper edge of the rear arm of the bell crank 15, adjacent such rocker, so that when the rocker is depressed, it will, through its engagement of the projection 51 thereof, with such bell crank, also effect the depression of the bell crank. The rocker will be restored to its normal position by the bell crank when the same is retracted by its spring. The rockers 50 are positioned so that the elongated bars thereof will directly oppose the foot portions of the various plates of the keys.

While a convenient embodiment of the invention is illustrated in the accompanying drawings, it will be understood that changes may be made to the particular form and construction therein shown without departing from the spirit and scope of the invention as defined in the appended claims.

I claim:—

1. A coin delivery machine comprising a series of coin pushers, operating means therefor including a series of levers, a series of rockers, one positioned adjacent each of said levers, each of said rockers being provided with a part projecting therefrom and overlying the lever adjacent thereto, and a series of keys for actuating said rockers.

2. A coin delivery machine comprising a series of coin pushers, operating means therefor including a series of levers, springs for normally holding said levers retracted, a movable member positioned alongside of each of said levers and having a part projecting therefrom and overlying one edge thereof, and a series of movable keys provided with portions adapted to engage said members when the keys are actuated.

3. In a coin delivery machine, the combination of a casing, of a series of coin pushers, a series of transversely aligned spring actuated bell crank levers for operating the push-

ers, a rocker positioned alongside of one arm of each of said bell crank levers and provided with a projection extending therefrom and overlying said arm, and means for actuating said rockers singly and associated.

4. In a coin delivery machine, the combination with a series of coin containers and pushers therefor, of means for operating the pushers comprising a series of associated pivoted levers, keys, and rockers operatively associated with the keys, each rocker having

a projection arranged to engage a lever, the various projections being in alinement with each other whereby the operation of the parts is rendered relatively uniform.

15

In testimony whereof I affix my signature in presence of two witnesses.

EDWARD J. BRANDT.
